(57) **CLAIM**

The ornamental design for a hand-held self-defense tool as shown and described.

DESCRIPTION

FIG. 1 is a top perspective view of a hand-held self-defense tool, showing my new design;

FIG. 2 is a bottom perspective view of a hand-held self-defense tool;

FIG. 3 is a side perspective view of the hand-held self-defense tool;

FIG. 4 is a top perspective view of a hand-held self-defense tool;

FIG. 5 is a top perspective view of a hand-held self-defense tool;

FIG. 6 is a top perspective view of a hand-held self-defense tool;

FIG. 7 is a top perspective view of a hand-held self-defense tool;

FIG. 8 is a top perspective view of a hand-held self-defense tool;

FIG. 9 is a top perspective view of a hand-held self-defense tool;

FIG. 10 is a top perspective view of a hand-held self-defense tool;

FIG. 11 is a top perspective view of a hand-held self-defense tool;

FIG. 12 is a top perspective view of a hand-held self-defense tool with a handle depicted on the body of the tool;

FIG. 13 is a side perspective view of a hand-held self-defense tool of FIG. 12;

FIG. 14 is a top perspective view of a hand-held self-defense tool with the handle of FIG. 12 depicted as broken lines;

FIG. 15 is a top perspective view of a hand-held self-defense tool with a wrapped handle depicted on the body of the tool; and,

FIG. 16 is a side perspective view of a hand-held self-defense tool of FIG. 15.

The broken lines depict portions of embodiments of the hand-held self-defense tool that form no part of the claimed design.

1 Claim, 16 Drawing Sheets
